UNITED STATES PATENT OFFICE

PIERRE J. CHÉRON, OF STRATFORD, CONNECTICUT, ASSIGNOR TO MOTO METER GAUGE & EQUIPMENT CORPORATION, OF TOLEDO, OHIO, A CORPORATION OF DELAWARE

DESIGN FOR A COVER PLATE FOR TRAFFIC WARNING DEVICE

Application filed February 26, 1931. Serial No. 38,828. Term of patent 7 years.

To all whom it may concern:

Be it known that I, PIERRE J. CHÉRON, a citizen of the United States of America, residing at Stratford, county of Fairfield, State of Connecticut, have invented a new, original, and ornamental Design for Cover Plate for Traffic-Warning Device, of which the following is a specification, reference being had to the accompanying drawings, forming part thereof.

Figure 1 is a front elevation of a cover plate for traffic warning device embodying my new design.

Figure 2 is an edge view of the same.

I claim:

The ornamental design for a cover plate for traffic warning device, as shown.

In testimony whereof I have signed my name to this specification.

PIERRE J. CHÉRON.
